UNITED STATES PATENT OFFICE

ERNEST H. ADAMS, OF LOS ANGELES, CALIFORNIA

PIPE CLEANING MACHINE

Application filed March 28, 1931. Serial No. 525,514.

This invention relates to pipe cleaning machines, and has for an object the provision of a pipe cleaning machine which is readily portable and of relatively small size and weight and, therefore, better suited for relatively small jobs of pipe cleaning.

A more detailed object is the provision of a pipe cleaning machine having an annular rotor head adapted to encircle the pipe to be cleaned, means for rotating the head, and a plurality of flexible abrading members such as chains secured to the head at points spaced circumferentially with respect thereto, these flexible members being tensioned into frictional engagement with the pipe, and of such a nature that they are capable of thoroughly cleansing the exterior surface thereof when the head is rotated with respect thereto.

Another object is to provide means for simultaneously relieving the tension upon all of the abrading members, so as to permit the pipe cleaning machine to be advanced along the pipe and past a relatively large portion thereof, such as that presented by a joint between two pipe sections, regardless of whether the joint be of the welded type or employ an interiorly threaded sleeve.

A further object is to form the rotor head in such a manner, and to so engage the flexible abrading members therewith, that the pipe cleaning machine may be mounted in operative position upon the pipe to be cleaned and removed therefrom relatively quickly and easily.

The invention possesses other objects and advantageous features, some of which, with those enumerated, will be set forth in the following description of the invention's particular embodiment which is illustrated in the drawings accompanying and forming a part of the specification.

Referring to the drawings:

Fig. 1 is a view in side elevation of a pipe cleaning machine embodying the principles of the present invention.

Fig. 2 is a vertical longitudinal sectional view, the actuating motor, however, being illustrated in side elevation.

Fig. 3 is a transverse vertical sectional

view, the plane of section being taken upon the line 3—3 of Fig. 1, and the direction of view indicated by the arrows.

Fig. 4 is a compound transverse vertical sectional view, the planes of section being taken upon the lines 4—4 of Fig. 1, with the direction of view as indicated.

Fig. 5 is a transverse vertical sectional view of the rotor head, the plane of section being taken upon the line 5—5 of Fig. 1, with the direction of view as indicated by the arrows.

Fig. 6 is another transverse vertical sectional view of the rotor head, the plane of section being taken upon the line 6—6 of Fig. 1, with the direction of view as indicated by the arrows.

In terms of broad inclusion, the pipe cleaning machine of the present invention comprises a carriage provided with means for movably supporting it upon the pipe to be cleaned. A motor of any suitable type mounted upon the carriage is operatively connected to a rotor head encircling the pipe below the carriage, so as to effect rotation thereof, and this rotor head is provided with a plurality of flexible abrading members such as chains under tension between points spaced circumferentially with respect to the head, so as to cause the abrading members to be pressed into frictional engagement with the exterior surface of the pipe, whereby scraping action between the abrading members and the pipe is established when the head is rotated.

Specifically describing a preferred embodiment of my improved pipe cleaning machine, I have provided a carriage, indicated in its entirety at 11, a motor 12 of any suitable design mounted thereupon, and a rotor head 13 adapted to encircle the pipe 14 to be cleaned, and disposed preferably directly below the carriage 11.

The carriage 11 comprises a frame in the form of a pair of longitudinally extending bars 16, each of which is deflected downwards, as at 17, at each end, presenting brackets upon each side of the pipe 14, and spaced slightly from each end of the rotor head 13. A horizontal bracket 18 extends

from each end of the frame and carries a roller 19 which engages the upper surface of the pipe 14, as best illustrated upon Figs. 1 and 2. Each of the rollers 19 is journaled by means of a pin 21 within a U-shaped member 22 adjustably secured to the associated bracket 18 by means of a bolt 23 or its equivalent, which extends through the bracket 18, being adjustably secured thereto by means of a nut 24 engaging each side of the bracket 18 and threaded upon the bolt 23. Thus, it may be seen that the effective height of the carriage 11 with respect to the pipe 14 may be varied, thereby making it possible to center the annular rotor head 13 with respect to the particular size of pipe 14 being cleaned. The rollers 19 also facilitate advancing the pipe cleaning machine along the pipe 14 during the cleaning operation, for which purpose preferably a plurality of handles 26 are provided, each of these handles 26 being rigid with the carriage 11 and extending to a position where they may be grasped conveniently by operators walking alongside the pipe 14. Obviously, if the pipe 14 is above the surface of the ground, handles 26 of different configuration will be employed, as compared with the handles used when the pipe being cleaned is disposed within a ditch or trench.

Although the motor 12 illustrated is an electric motor, obviously any other type of prime mover may be employed, the only requirement being that it be of sufficient capacity to provide the force necessary to effect rotation of the rotor head 13, as will readily be understood.

The rotor head 13 comprises a pair of annuluses 31 and 32 rigidly interconnected and retained in spaced axial relationship by means of a plurality of stay bolts 33. The two annuluses 31, 32 are split diametrically as at 34, in a common plane, thereby presenting a pair of rotor head sections 36 and 37, each of which is substantially semi-circular in cross sectional configuration. The sections 36 and 37 are pivotally joined at one side by any suitable hinge construction 38, and are adapted to be releasably interconnected along the other side by means of a bolt 39 pivoted to a lug 41 rigid with one of the sections, say the section 36, and adapted to extend through a bifurcated lug 42 rigid with the other section 37. Hence, when a nut 43 threaded upon the bolt 39 is tightened, the two sections 36 and 37 will be releasably but firmly clamped in annular form. This construction makes it possible to position the rotor head 13 upon a pipe 14 without the necessity of having to slip the head over an end of the pipe. Instead, the head 13 may be opened by release of the bolts 39 wide enough to permit slipping the head laterally onto the pipe, after which the sections 36 and 37 may be swung to closed position with

the head encircling the pipe 14, and the bolts then tightened.

An annular groove 46 is formed in the outer face of each of the annuluses 31 and 32 for the reception of preferably a plurality of rollers 47 journaled upon pins 48 which are carried by a bar 49 extending between the brackets 17 at the associated end of the head 13. Hence, the rotor head 13 is interconnected with the carriage 11 in such a manner that the head may rotate freely with respect thereto, but is caused to advance along the pipe 14 as the carriage 11 is advanced. An annular flange 51 on one of the annuluses, say the annulus 31, is provided with a preferably V-shaped groove 52 for the reception of a belt 53 which also engages a pulley 54 carried by the shaft 56 of the motor 12, whereby energization of the motor 12 results in rotation of the rotor head 13.

The rotor head 13 carries preferably a plurality of flexible abrading members 57 which are in frictional engagement with, and which either partially or completely encircle the pipe 14, so as to develop the scraping or abrading action necessary to thoroughly cleanse the exterior surface of the pipe when the head 13 is rotated. For these abrading members 57 I prefer to employ chains, the links of which are provided with outwardly extending projections or points for scraping and cleaning the pipe 14.

The means for mounting the chains 57 upon the rotor head 13 is in the form of a plurality of rods 58 rigid with and extending between the corresponding sections 36, 37 of the two annuluses 31 and 32. These rods 58 are disposed upon opposite sides of and closely adjacent the diametrical plane within which the rotor head 13 is split, as best illustrated upon Fig. 4. Carried by each of the rods 58 is a bar 59, each rod 58 and its bar 59 being adjustably interconnected by means of a bolt 60 adjacent each end thereof and threaded through the rod 58, and extending through a clearance hole in the bar 59, there being a nut 61 or other suitable abutting shoulder rigid with the bolt 60 upon each side of the bar 59 so as to retain the bar 59 in selected spaced relationship with respect to the rod 58. A plurality of hooks 62 have their shanks 63 extending slidably through each of the rods 58, and these shanks, which preferably are threaded, also extend through the associated bar 59 and each carries a nut 64 in engagement with that face of the bar 59 which is remote from the hook 62. Hence, each of the hooks 62 may be individually adjusted by manipulation of its associated nut 64 or all of the hooks 62, the shanks 63 of which extend through any one of the rods 58, may be simultaneously adjusted by manipulation of the associated bolts 61, whereby the bar 59 with which those hooks 62 are con-

nected is retained in spaced relationship with the rod 58.

The chains 57 are under tension between the hooks 62 of different rods 58, and inasmuch as these rods are spaced circumferentially with respect to the rotor head 13, the tension imposed upon the chains will cause the chains to wrap themselves about and come into frictional engagement with the exterior surface of the pipe 14. The chains 57 may be engaged upon the hooks 62 in various manners. For example, each chain may be relatively short and engaged at its ends upon hooks 62 of only one of the head sections 36 or 37, under which circumstances each chain will make contact with the pipe 14 throughout substantially 90° of arc. Or, if desired, the chains may be relatively long and extend almost completely around the pipe 14, so as to be engaged at its ends with hooks carried by rods 58 on both sections 36 and 37, and upon the same side of the rotor head. The stay bolts 33 are provided with spaced perforations and the chains 57 may be fastened to the stay bolts 33 by means of bolts 60 and nuts 61 in the same manner as described in connection with the rods 58.

An advantage of this particular type of pipe cleaning machine is that it is considerably less subject to becoming clogged up with the extremely tenacious material with which the exterior surfaces of pipe lines are frequently provided so as to prevent deterioration of the pipe from rusting and the like. Those machines which employ rigid scrapers have been found to be more or less unsatisfactory, because of the fact that each scraper accumulates a ball of this coating material mixed with dirt, flakes of rust, and other material frequently to such an extent that the operation of the scraper itself is seriously interfered with. The chains 57 apparently are not subject to such unsatisfactory operation, especially when these chains are designed in accordance with my copending application, Serial No. 525,515, filed March 26, 1931. Moreover, the entire portion of the rotor head 13 within which the chains 57 are operative is open, thereby permitting material scraped from the pipe 14 to fall freely from the head, and thus preventing an accumulation of this material, as frequently occurs in other types of cleaning machines.

As has been stated hereinabove, it is intended that the cleaning machine shall be advanced along the pipe manually. As such advance takes place joints between pipe sections will be encountered at intervals, and when this takes place all the chains 57 can be loosened simultaneously by proper manipulation of the appropriate bolts 61, thereby permitting the cleaning machine to pass the joint, after which the chains may again be tightened. It should be explained, however,

that simultaneous loosening and tightening of all the chains can be effected only if an end of each chain is connected to a common rod 58. Fig. 4, however, illustrates the chains arranged with their ends in staggered relationship, i. e., one chain ends at one side of the head 13, the next chain ends at the other side of the head, and so on. Under such circumstances, half the chains may have their tension varied by manipulation of one set of bolts 61, and the other half of the chains by manipulation of another set of bolts 61, as will readily be understood.

It is to be understood that the details of the invention as herein disclosed, are subject to alteration within the spirit or scope of the appended claims.

I claim:

1. In a pipe cleaning machine, a rotor head comprising a pair of annuluses adapted to encircle a pipe, rods interconnecting said annuluses and spaced circumferentially with respect thereto, chains under tension between said rods and frictionally engaging said pipe, adjustable means interposed between said chains and said rods for varying the tension of said chains, and means for turning said head with respect to said pipe.

2. In a pipe cleaning machine, a rotor head comprising a pair of annuluses adapted to encircle a pipe, rods interconnecting said annuluses and spaced circumferentially with respect thereto, a plurality of chains under tension between said rods and frictionally engaging said pipe, means for varying the tension of all of said chains simultaneously, and means for turning said head with respect to said pipe.

3. In a pipe cleaning machine, a rotor head comprising a pair of annuluses adapted to encircle a pipe, rods interconnecting said annuluses and spaced circumferentially with respect thereto, a bar extending adjacent each of said rods, adjusting means for varying the distance between each of said bars and its associated rod, a plurality of hooks having shanks connected to each of said bars and extending slidably through the associated rod, and chains under tension between hooks of spaced rods and frictionally engaging said pipe.

4. In a pipe cleaning machine, a rotor head comprising a pair of annuluses adapted to encircle a pipe, rods interconnecting said annuluses and spaced circumferentially with respect thereto, abrading means engaging said pipe, said abrading means including a flexible member under tension between said rods, adjustable means interposed between said flexible member and said rods for varying the tension of said flexible member, and means for turning said head with respect to said pipe.

5. In a pipe cleaning machine, a rotor head comprising a pair of annuluses adapted to

encircle a pipe, rods interconnecting said annuluses and spaced circumferentially with respect thereto, abrading means engaging said pipe, said abrading means including 5 flexible members under tension between said rods, adjustable means interposed between said flexible members and said rods for varying the tension of said flexible members, means for turning said head with respect to 10 said pipe, and means for relieving the tension of all of said flexible members simultaneously.

In testimony whereof I have signed my name to this specification.
